UNITED STATES PATENT OFFICE.

GEORGE M. DUDLEY, OF TACOMA, WASHINGTON.

KINDLING-CHOPPER.

1,364,737.

Specification of Letters Patent.

Patented Jan. 4, 1921.

Application filed November 13, 1919. Serial No. 337,782.

To all whom it may concern:

Be it known that I, GEORGE M. DUDLEY, a citizen of the United States of America, residing at Tacoma, in the county of Pierce and State of Washington, have invented new and useful Improvements in Kindling-Choppers, of which the following is a specification.

The object of the invention is to provide a simple and efficient tool for household and similar use for producing kindling from fagots without resorting to the comparatively tedious use of a hatchet as in the ordinary practice and of such a form as to adapt it to split a stick or fagot into a number of small, readily ignitable pieces at a single stroke, and to this end the same consists in a construction and combination of parts of which a preferred embodiment is shown in the accompanying drawing, wherein:

Figure 1 is a sectional view of the same taken longitudinally of the handle.

Fig. 2 is a section on the plane indicated by the line 2—2 of Fig. 1.

nally thereof either by impact on the other end of the stick or fagot or by utilizing the head in the same way as a hatchet head is used in a splitting operation, and as a result the stick or fagot is divided according to the intervals between the intersecting cutting or knife edges into a plurality of small kindling sticks which may be readily ignited by a match or by the use of paper or the equivalent thereof.

In other words in the use of a tool such as described a stick or fagot may be divided into a number of kindling sections at a single blow or stroke as distinguished from the operation necessary by the use of a hatchet or ax where a single stroke produces a cut in only one direction or a division of a stick or block into two parts.

What is claimed is:

1. A kindling chopper having a head provided with a plurality of intersecting blades arranged to bound spaces which are transversely expanded progressively in a direction receding from the cutting edges of said blades.

2. A kindling chopper having a head consisting of a plurality of intersecting webs having cutting edges arranged in a common plane and disposed to form independent passages of which the walls diverge as they recede from the cutting edges.

3. A kindling chopper having a head consisting of a bounding wall inclosing a space spanned by webs disposed in intersecting planes and provided at one face of the head with reduced cutting edges, the spaces between the webs being progressively enlarged as they recede from the plane of the cutting edges.

In testimony whereof he affixes his signature.

GEORGE M. DUDLEY.
